ATTORNEY.

UNITED STATES PATENT OFFICE.

WILLIAM RABICH, OF ST. LOUIS, MISSOURI, ASSIGNOR OF ONE-THIRD TO PAUL ROTHE, OF ST. LOUIS, MISSOURI.

FOLDING FURNITURE.

No. 909,820.

Specification of Letters Patent.

Patented Jan. 12, 1909.

Application filed August 31, 1908. Serial No. 451,082.

To all whom it may concern:

Be it known that I, WILLIAM RABICH, citizen of the United States, residing at St. Louis, State of Missouri, have invented certain new and useful Improvements in Folding Furniture, of which the following is a full, clear, and exact description, reference being had to the accompanying drawings, forming a part hereof.

10 My invention has relation to improvements in folding furniture; and it consists in the novel construction and arrangement of parts more fully set forth in the specification and pointed out in the claims.

15 In the drawings, Figure 1 is a side elevation of a chair unfolded, showing my invention applied thereto; Fig. 2 is a front elevation of the same; Fig. 3 is a side elevation of the chair in a folded position; Fig. 4 is a 20 sectional detail on the line 4—4 of Fig. 1; and Fig. 5 is a sectional detail showing the plug in the bottom sockets of the chair-legs.

The present invention is an improvement 25 to in folding furniture of the character referred in my U. S. Patent 886,072 dated April 28, 1908, and has for its object to provide a folding arrangement which will materially simplify the construction of the article over that shown by the patent, such simplification 30 being particularly directed to the means for locking the piece of furniture (a chair in the present instance) in either its folded or unfolded position. It consists in further details of construction the advantages of which 35 will be readily apparent from a detailed description of the invention which is as follows:—

Referring to the drawings, 1, 1, 2, 2, represent two folding frames or members hinged 40 about the opposite ends of a rod 3, the lower ends of the members terminating in sockets 4 for the insertion of wooden or rubber or composition plugs 5, which when resting on the floor will not scratch the same. The 45 members 1, 1, are extended upwardly as shown by 1', 1', said extensions forming the sides of the back of the chair. The back may be finished in any approved manner and for a plain chair may be provided with 50 slats a.

The upper ends of the members 2, 2, are connected by a transverse rod 6, the opposite ends of which play freely in the slots s of

the members 7 forming the side metal strips of the seat S. The rear ends of the members 55 7 turn upwardly and terminate in loops 8 adjacent to the members 1, 1, said loops loosely encompassing a rod 9 connecting the members 1, 1, immediately above the rear of the seat S. The rod 9 is loosely embraced 60 also by the lower ends of the metal members b which enter into the construction of the back. To the projecting ends of the rod 6 are pivotally coupled the forward ends of the curved connecting side links 10, the rear 65 ends of said links terminating in outwardly projecting buttons 11, the shanks of which travel in the slots s' of the forwardly enlarged portions of the arm-rest links 12, hinged to the bases of the extensions 1', 1'. 70 The links 12 are provided with lobes 13 to which the wooden arm-rests 14 are secured. The forward end of the slot s' terminates in an upwardly-directed recess r into which the button 11 (or rather the shank thereof) 75 settles behind a cam formation or rounded shoulder 15 for the unfolded position of the chair. The forward end of the link 10 terminates in an inwardly deflected finger d which, for the folded position of the chair 80 settles snugly against the adjacent curved edge of the upper end of the member 2, said edge serving as a bearing for the finger, the friction between the parts preventing any accidental unfolding of the chair. To open 85 the chair the friction between the finger d and the member 2 must be overcome by the operator.

When the chair is unfolded, it will remain so even when picked up by seizing the same 90 by the back, since the shoulders 15 frictionally lock the links 10 against any rearward travel along the slotted arm-rest links 12. By seizing the free end of the seat with one hand however, and the upper end of the 95 back with the other hand, then pulling or swinging the seat toward the back, the buttons 11 will become dislodged from the recesses r and caused to travel in the slots s'. At the same time the rod 6 will travel rearwardly along the slots s and the desired collapse of the chair takes place (Fig. 3). The purpose of the fingers d has already been alluded to; suffice it to say however, that when the friction between them and their 100 abutments 2, 2, has been overcome by a 105

swinging of the seat away from the back, the chair will unfold, assuming the position shown in Fig. 1.

Having described my invention, what I claim is:—

1. In a folding chair, two pairs of members in hinged relation to one another, one pair having extensions forming the sides of the chair-back, a seat hinged at the base 10 of the extensions, slotted members disposed at the sides of the seat, arm-rest slotted links hinged to the bases of the extensions, links having their upper ends free to travel in the slots of the arm-rest links, a transverse rod 15 coupling the upper ends of one pair of the hinged members and traveling in the slots of the slotted members of the seat, the lower ends of the links being hinged to the ends of the transverse rod, substantially as set 20 forth.
2. In a folding chair, two pairs of members in hinged relation to one another, one pair having extensions forming the sides of the chair-back, a seat hinged between the 25 bases of the extensions, slotted members

forming the sides of the seat, slotted arm-rest links hinged at one end to the bases of the extensions, the forward ends of the slots having upwardly directed recesses provided with a cam formation or shoulder at the 30 forward terminals of the slots, connecting links having buttons traveling in said arm-rest slots, a transverse rod coupling the upper ends of the shorter pair of hinged members and traveling in the slots of the 35 slotted seat-members, the ends of the rod being in hinged connection with the adjacent ends of the connecting links, and inwardly directed fingers formed on the hinged ends of the last named links for engaging 40 the adjacent edges of the shorter pair of hinged members for the folded position of the chair, substantially as set forth.

In testimony whereof I affix my signature, in presence of two witnesses.

WILLIAM RABICH.
